ABRAM N. PASMAN, OF EAST ORANGE, NEW JERSEY.

FLUSH-VALVE APPARATUS.

1,225,352.

Specification of Letters Patent.

Patented May 8, 1917.

Application filed December 1, 1916. Serial No. 134,285.

To all whom it may concern:

Be it known that I, ABRAM N. PASMAN, a citizen of the United States, residing at East Orange, in the county of Essex and 5 States of New Jersey, have invented an Improvement in Flush-Valve Apparatus, of which the following is a specification.

This invention relates to the chain pull type of flush valves employed with tanks 10 or other receptacles commonly used in flushing toilets or other places where at certain times a predetermined flow of water is required. Heretofore various forms of chain pull flush valves have been employed. In 15 this type of flush valve in use at one time, the valve was so constructed as to open by pulling the chain and to close immediately when the chain was released, and in its use it was necessary therefore to actually hold 20 the valve open until the required flow of water was obtained. More recently, and taking the place of this type of valve to a large extent, a siphon flush valve has been employed. The siphon valves, however, 25 are relatively expensive, and are also likely to get out of order at frequent intervals, and the object of the present invention is to provide an inexpensively constructed flush valve in which the flow of the water 30 through the same is maintained while in an open position until the water in the tank or other reservoir reaches a predetermined level when the valve automatically closes; and the invention also includes a means for regulating the valve to close at different water 35 levels in the tank or reservoir for the purpose hereinafter indicated.

The flush valve made in accordance with my invention will be hereinafter more particularly described in connection with the accompanying drawings forming part of this specification, and in which Figure 1 is a sectional elevation illustrating my improved flush valve as applied to a supply 45 tank. Fig. 2 is an enlarged sectional view of the same. Fig. 3 is an inverted plan showing the construction of the operating parts of the valve. Fig. 4 is a plan of the modification shown in Fig. 5 which is a 50 sectional elevation illustrating the means by which the valve is caused to close at different water levels in the supply tank or reservoir.

In the drawing, 10 indicates a tank or 55 reservoir as commonly employed to flush toilets and other similar places where a

pull chain flush valve is installed. As is customary in such instances, I employ a pipe fitting 11 passing through and fixed in the bottom of the tank. Beneath the tank 60 a flush pipe 12 is suitably connected to the fitting 11, which at its inner end and within the tank terminates in an annular extension or body member 13, the extremity of which acts as a valve seat. The valve is 65 preferably so constructed as to comprise a disk head 15 carrying a washer 16 placed between the same and the inner end 17 of the valve head. The washer 17 is adapted to seat against the extremity of the body 70 member 13, and the inner end 17 of the head to fit within a recess 18 provided therefor 75 interiorly at the extremity of the body member. Secured to the valve head I employ a number of radially placed blades 19, which are suitably connected to the valve 80 head and adapted to fit within the body member 13 so as to act as guides in the movement of the valve in the opening and closing thereof. In the drawing, three of 85 these blades are illustrated, but it will be understood that the invention is not limited to this number. There being three blades 19 illustrated in this instance, the interior of the body member 13 is divided into compartments 20, 21, and 22 through which as 90 it will be understood when the valve is open, the water from the tank will flow through the body member 13 of the fitting, and thence to the flush pipe 12 leading to the 95 closet or other devices to be flushed.

Associated with one of the blades 19 so as to lie within the compartments 21 and 22, I employ vanes indicated at 23. These are pivotally connected to one of the blades 19 as 95 indicated at 24, and are so constructed as to be rights and lefts with the corresponding sides 25, lying against the blade to which they are pivotally connected, while the faces 26 of the valves when the valve is open, as 100 shown in Fig. 2, are forced by the water pressure flowing into the compartments 21 and 22, so as to lie against the adjacent faces of the other blades 19. The inner extremities of the vanes 23 are curved as indicated 105 at 27, and the extremities of the vanes beyond their pivotal points at the opposite ends are provided with square corners or lugs 28 adapted when the valve reaches a certain point in moving toward its seat to 110 contact with the edge defining the recess 18. Due to the weight of the valve this contact

has a tendency to swing the vanes in the opposite direction against the pressure of the flowing water. Consequently as long as the water pressure is sufficient to maintain the 5 vanes in such positions that the lugs 28 bear on the edge defining the recess 18 it will hold the valve in an open position and the water will continue to flow, this action being assisted by the curved ends 27 of the vanes. 10 When however the water level in the tank is lowered sufficiently far to reduce the pressure to such an extent that it will no longer support the valve, the valve continues its inward movement, by gravity, until it 15 reaches its seat, and in which movement the lugs 28 ride over the edge defining the recess 18 and the vanes assume the positions indicated in Fig. 1 of the drawing.

The disk head of the valve is connected to 20 a tube 29 which acts both as a means for lifting the valve, and as an overflow for the tank. The upper end of the tube 29 is connected to the inner end of a lever 30 by means of a chain 31. The lever 30 is pivotally mounted in a bracket 32 suitably connected to the tank or other support, and at its opposite end has attached thereto a pull chain 33 by which the valve may be raised from its seat.

30 In order to regulate the time in which the valve will close and also the consequent flow of water through the same as well as to obviate any disagreeable noise caused by the mingling of the air with the water just 35 before the valve closes, I may, as indicated in Figs. 4 and 5, provide the valve head with an annular rim or flange 34 made concentric with the tube 29, and forming a pocket or water chamber 35. The annular rim 34 is 40 fitted with a sleeve 36 surrounding the same and revoluble thereon. In the annular rim 34 there is a slot 37, preferably made at an inclination as shown in Fig. 5, and in the sleeve 36 is an aperture 38. By this construction, as will be apparent the valve may 45 be weighted by adjusting the relative positions of the slot 37 and the aperture 38 so as to retain in the pocket a predetermined quantity of water when the tank is emptied, and 50 by so doing the valve may be regulated to seat when different and predetermined water levels above the valve seat in the tank have been reached.

I claim as my invention:

55 1. A flush valve comprising a tubular body member having a seat, a valve adapted to bear against the said seat, and a vane movably connected to the said valve and actuated by pressure exerted against one portion 60 thereof by the medium flowing through said tubular body member to cause another portion thereof to bear directly against a part of the said tubular body member to maintain the valve in an open position.

65 2. In a flush valve apparatus and in com-

bination, a tank, a flush valve comprising a tubular body member having a seat, a valve head adapted to bear against the said seat, and vanes pivotally connected to the said valve head and actuated by pressure exerted 70 against corresponding portions thereof by water flowing through the said tubular valve member to cause other portions thereof to bear directly against a part of the said tubular body member in order to maintain the valve in an open position until the water in the tank is lowered to a predetermined level. 75

3. In a flush valve apparatus and in combination a tank, a flush valve comprising a tubular body member having a seat, a valve 80 head adapted to bear against said seat, means connected to the said valve head, movable therewith, and actuated by the pressure of water flowing through the body member to coöperate with the said body member in 85 order to maintain the valve in an open position until the water in the tank is lowered to a predetermined level, and adjustable devices associated with the said valve for determining the water level in the tank at 90 which the valve will close.

4. In a flush valve apparatus and in combination, a tank, a flush valve comprising a tubular body member having a valve seat at the inner end thereof, a valve head adapted 95 to bear against the said seat, blades secured to the said valve head and fitting within the said body member to guide the valve head in the movements thereof, and means carried by the said blades and bearing directly 100 against the body member by the pressure of the water flowing therethrough to maintain the valve head in an open position until the supply in the tank has been lowered to a predetermined level. 105

5. In a flush valve apparatus and in combination, a tank, a tubular body member fixed in the tank and having a seat at its inner end, a valve head adapted to bear against the said seat, radially placed blades 110 secured to the said valve head and adapted to fit within the valve body to guide the valve head in the movements thereof, and vanes pivotally connected to the said blades and coacting with said body member against the pressure of the water flowing therethrough to maintain the valve in an open position until the supply in the tank has 115 reached a predetermined level.

6. In a flush valve apparatus and in combination, a tank, a tubular body member fixed in the tank and having a seat at its inner end, a valve head adapted to bear against the said seat, radially placed blades 120 secured to the said valve head and adapted to fit within the valve body to guide the valve head in the movements thereof, vanes pivotally connected to the said blades, and means operative after the valve head and blades have moved a predetermined distance 125 130 135

toward the valve seat to contact with the body member and by the water pressure acting against said vanes to maintain the valve head in an open position until a predetermined water level has been reached in the tank.

7. In a flush valve apparatus and in combination, a tank, a tubular valve body fixed in the tank and having a seat at its inner end, a valve head adapted to bear against the said seat, radially placed blades secured to the said valve head and adapted to fit within the valve body to guide the valve head in the movements thereof, vanes pivotally connected to the said blades and coacting with said body member and the pressure of the flowing water to maintain the valve in an open position until the supply in the tank has reached a predetermined level,

10 8. In a flush valve apparatus and in combination, a tank, a flush valve comprising a tubular body member having a valve seat at the inner end thereof, a valve head adapted to bear against the said seat, blades secured to the said valve head and fitting within the said body member to guide the 15 valve head in the movements thereof, means associated with the said blades and coacting with said body member against the pressure of the flowing water to maintain the valve head in an open position until the supply in the tank has been lowered to a predetermined level, and adjustable means for determining the water level in the tank at which the valve will close.

9. In a flush valve apparatus and in combination, a tank, a tubular valve body fixed in the tank and having a seat at its inner

end, a valve head adapted to bear against the said seat, radially placed blades secured to the said valve head and adapted to fit within the valve body to guide the valve 45 head in the movements thereof, vanes pivotally connected to the said blades and coacting with said body member and the pressure of the flowing water to maintain the valve in an open position until the supply 50 in the tank has reached a predetermined level, and adjustable means for determining the water level in the tank at which the valve will close.

10. In a flush valve apparatus and in combination, a tank, a tubular valve body fixed in the tank and having a seat at its inner end, a valve head adapted to bear against the said seat, radially placed blades secured to the said valve head and adapted to fit 60 within the valve body to guide the valve head in the movements thereof, vanes pivotally connected to the said blades, the said vanes being curved at their inner ends, lugs on the said vanes adapted to coact with a 65 portion of the said valve body against the water pressure on said vanes to maintain the valve in an open position until the supply in the tank has reached a predetermined level, an annular rim connected to the valve 70 head, and having a slot therein, and a sleeve revoluble on the annular rim and having an aperture therein coacting with the slot in the annular rim to retain a predetermined quantity of water within the pocket formed 75 by the annular rim, and thus weight the valve to determine the water level in the tank at which the valve will close.

Signed by me this second day of November, 1916.
